UNITED STATES PATENT OFFICE.

CARL HUGO THORNBLADE, OF SEATTLE, WASHINGTON, ASSIGNOR TO ORIGINAL COPY-
WRITER CO., A CORPORATION OF WASHINGTON.

MULTICOPY ATTACHMENT.

Application filed April 12, 1927. Serial No. 183,062.

- My invention relates to typewriters and consists of an attachment designed for application to machines already built, whereby additional type ribbons may be placed between the paper sheets so that more than one copy may be made at one time, all originals in the sense that all are written in ink, as is the first copy when carbon sheets are employed in the customary practice.
- 10 The object of my invention is to substitute inked ribbons for the carbon papers, thereby producing several ink-written copies, instead of one ink copy and carbon copies, and to do this by a device which may be readily applied
- 15 to a typewriter when its use is desired, and detached therefrom when its use is not desired.

It consists of the special constructions which are illustrated in the accompanying drawings, and which will be hereinafter described and then specifically defined by the claims.

In the accompanying drawings I have illustrated my invention embodied in the type 25 of construction as first designed by me.

Figure 1 is a side elevation of the carriage mechanism of a standard make of typewriter, my attachment being in place and shown in a cross section taken on a plane just inside the 30 inner face of one of the wings of the case or frame, or upon the plane indicated by the broken lines 1, 1 of Figure 3.

Figure 2 is a section taken on a transverse plane at any point between the wings.

35 Figure 3 is a plan view of the device upon a typewriter carriage, one wing case being in section, together with a small part of the cross connecting shafts and the connecting frame section.

40 Figure 4 is a front elevation of one wing frame or casing.

My device has been designed as an attachment which may be readily put in place and removed, and when in place will enable the 45 insertion of one or more inked ribbons between the sheets of paper which have been together inserted in the typewriter ready for writing thereon.

As a support for the device, a base or 50 journal plate 1 is secured at each end of the typewriter carriage. These extend upwardly, and toward the rear of the typewriter carriage are each provided with a journal or analogous means for receiving and holding

the main frame in accurate position relative to the writing platen.

The means illustrated consists of a finger 55 10 having an arcuate inner edge of materially less than 180°, with an outwardly inclined end edge 11, this acting in conjunction with a similarly formed finger carried by a plate 12 which is pivoted at 13 upon plate 1, and has its finger 12 held toward the first finger 10 by a spring, as 14. A plate 15 is shown as secured in spaced relation to plate 1, the plate 12 lying between and being supported by these two plates.

The pivoted frame which carries the ink 60 ribbons contains two wings or flat cases 20, and a member connecting the rear parts of 70 said wings, herein shown as a tube 2. Journaled in the connecting section 2 is a shaft 65 for each extra inking ribbon used. As two such ribbons are shown in the drawings, two shafts 3 and 30 are shown, these being tubes, 75 one within the other, and both within the tube 2 of the frame.

Each shaft 3 and 30 carries an operating 80 arm 4 and 40, respectively, these extending forwardly within the hollow wing casing 20. One face of each wing case would be made removable, or otherwise constructed to make access to its interior easy. Each wing section has guide ways 21, 22, which, together with guide rods 23, support and guide the ribbon holding fingers 5 and 50. These fingers and guides are so constructed and positioned that the ink ribbons 52 carried by the lower ends of said fingers will be positioned close in front of the printing line of the platen and back of the usual typewriter ribbon, when 90 the fingers are in their lowermost position. As illustrated, these fingers are straight, as are also the guides 21 and 22, although it is evident that the character and position of the guides and the fingers might be modified, if 95 they secured the essential feature of placing and holding the ribbons in proper printing position and, when raised, held said ribbons out of the way.

The lower ends of the fingers 5 and 50 are 100 provided with means for securing the ends of the ribbons 52. This may simply consist of a slight hook tip 55 which enters loops 56 formed upon the ends of the ribbons. To 105 provide a resilient holding effect acting to keep these ribbons taut, a spring, as 53, may be provided to act upon each finger. To pre-

vent swinging of the fingers 5 and 50, when the ribbons are removed, so as to engage the hook 55 with any part of the machine, a spacing foot 54 is provided for each ribbon-holding finger, these engaging the face of the wing cases 20.

Each arm 4 and 40 is operatively connected with its respective finger 5 or 50, so that when the shaft to which they are secured is oscillated, the arms 4 and 40 will swing and cause the ribbon-holding fingers to be reciprocated. As shown, this is done by employing a pin or finger, as 57, 58, carried by the ribbon-holding finger, and slotted ends 41, 42 on the arms. Each arm 4 and 40 at one end of the device has a manually engageable finger 43 or 44 projecting through slots 23' in the outer face of the wing casing 20, whereby the shafts 3 and 30 may be rocked, thereby shifting the ribbon-holding fingers into and out of operating position.

The bearing brackets 1 are to be fixed to the ends of the carriage frame. The rest of the device is mounted upon a self-contained frame so that it may be removed bodily when not wanted. In applying it to the carriage, the tubular member 2 of the frame is forced between the fixed and movable fingers 10 and 12, the member 12 yielding backward, and on its return holding the frame in exact position. It may be removed by lifting out from between the fingers.

By the use of this device, an ordinary typewriter may be equipped to make three or more ink copies at one time, which, for certain purposes, as for making papers of record, may be of great advantage. The application of the device to a typewriter does not interfere with its use in making carbon copies by the use of carbon paper sheets.

What I claim as my invention is:

1. A duplicator for typewriters, comprising two vertically-disposed cases and a tubular member connecting the rear ends of said cases to form a rigid frame holding said cases over opposite ends of the typewriter carriage, and forming a pivot axis upon which the cases may be swung, a shaft mem-

ber journaled within said tubular frame member, an arm fixed to each end of said shaft and lying within said cases, vertically-extending fingers having supporting and guiding engagement upon the forward ends of said cases and having operative engagement with said arms, and a writing ribbon extending between fingers of opposite ends and adapted to be held in front of the printing line of the typewriter platen when the fingers are in lowered position.

2. A duplicator attachment for typewriters, comprising a frame composed of a tubular connecting bar sections and wing sections extending laterally from the ends of said connecting section, said frame being adapted to be pivotally mounted by said connecting section upon the rear part of a typewriter carriage with the wing sections at each end of the carriage, a shaft journaled in the said tubular connecting bar, an arm secured to each end of said shaft, fingers having vertical guide supports at the forward part of said wing sections and adapted to be projected downwardly, said fingers having operative engagement with the arms to be thereby reciprocated when the arms are swung, and a printing ribbon extending between the fingers and positioned in front of the printing line upon the platen when the fingers are down.

3. In a duplicator attachment for typewriters, a frame comprising a central connecting section and wings extending laterally from the ends thereof, means for supporting a printing ribbon to extend between said wings, and means for raising said ribbon when desired, and spring held journal clamping members securable upon the typewriter carriage, said connecting section of said frame being adapted to be pivotally engageable with and disengageable from said journal clamping members, thereby to easily attach and remove said attachment.

Signed at Seattle, King County, Washington, this 25th day of March, 1927.

CARL HUGO THORNBLADE.
